UNITED STATES PATENT OFFICE.

STANLEY N. JUTHE, OF NEWTON, AND SIDNEY H. LANG, OF CAMBRIDGE, MASSACHUSETTS.

DESIGN FOR AN AERIAL TOY.

56,171.

Specification for Design.

Patented Aug. 24, 1920.

Application filed April 21, 1920. Serial No. 375,634. Term of patent 3½ years.

To all whom it may concern:

Be it known that we, STANLEY N. JUTHE and SIDNEY H. LANG, citizens of the United States, and residents, respectively, of Newton, county of Middlesex, State of Massachusetts, and Cambridge, county of Middlesex, State of Massachusetts, have invented a new, original, and ornamental Design for an Aerial Toy, of which the following is a specification, reference being had to the accompanying drawing, forming part thereof.

In the drawings, Figure 1 is a plan view of a toy showing our new design;

Fig. 2 is a side view thereof;

Fig. 3 is a section on the line 3—3, Fig. 2;

Fig. 4 is a section on the line 4—4, Fig. 2.

We claim:

The ornamental design for an aerial toy, as shown.

STANLEY N. JUTHE.
SIDNEY H. LANG.
